FLASHLIGHT HOLDER

Julius Schafranek, Newark, N. J.

Application August 14, 1946, Serial No. 690,491

5 Claims. (Cl. 248-359)

1

This invention relates to a holder especially adapted for holding a flash light. It happens a great many times that an individual wishes he had someone or something to hold a flash light so both hands can be utilized in the operation where the light is required to see how to do the work.

I am aware of the fact that numerous structures have been proposed for holding a flash light but I have found from experience that they are more or less crude in construction, awkward to handle and relatively expensive and do not satisfactorily serve the very purpose for which they were intended.

It is therefore the principal object of my invention to provide a flash light holder which will overcome the aforesaid objections and the improved structure is set forth in the following specification taken in connection with the annexed drawing, wherein,

Figure 1 is a perspective view showing the holder in one position, the flash light per se not being shown.

Figure 2 is a view of the structure shown in Figure 1 with the base in upside down position, folded up and in a position for packaging and shipping.

Figure 3 is a view of a modified form of the construction.

Figure 4 is a view of the structure shown in Figure 3 folded up for packing and shipping purposes.

In Figures 1 and 2, B is a base made from a single piece 1 of suitable stiff material such as rust-proof steel or a suitable chrome alloy. The ends of the wire 1 are formed into a projection 2 with the ends coming together as indicated by the dotted line 3 in Figure 2. Preferably the parts forming the projection 2 come together at 3 and may be butt or spot welded at that point. At the beginning of the projection 2 the parts preferably come together at 4 and are spot welded at this point. Attached to the projection 2 of the base B is a support member 5 formed of a single piece of suitable metal. The member S is L-shaped in formation having long arm 5 and a short arm 6. The arm 6 is bent around the projecting part 2 of the base B, as indicated, thereby covering the joint 3. It will be seen from Figure 1 that the short arm 6 extends over and rests on the projection 2 of the base B when the arm 5 is in vertical position, thereby giving a substantial bracing effect to the support S. The upper or free end of the long arm 5 is bent over at 24 and this bent-over portion 24 has 55

2

a part 7 formed somewhat cup-shaped and likewise the part of the arm 5 opposite the portion 24 has a similar formation 8 to provide a seat for a ball 9. The ball 9 has a stem 10 fastened thereto and to this stem is fastened a member 11 of suitable resilient material having outwardly curved lips 12 and 13 to assist in mounting the flash light into member 11. As shown in Figures 1 and 2, the arm 5 has a threaded hole therein to receive a stud 14 having a head 15 whereby the part 24, which has considerable resilience, may be adjusted to give the right amount of friction to the ball 9 so that the holder 11 may be turned around at any angle 16 through 360° at the same time it may be moved in another direction approximately 180° by reason of the stem 10 moving in the slot 16 of the ball seat.

I prefer the construction just described although the part 24 may have sufficient strength and resilience so the adjusting stud 14 will not be required and any adjustment required can be done by applying a force directly to the part 24. From what has been said it will be readily seen that the flash light carried by the holder can be adjusted to a multitude of positions. The structure just described is such that the base B can be slipped back of one's belt and the support member adjusted to any position to properly locate the flash light so that the operator can move around and carry the flash light with him both hands free. As shown in Figure 2 the support member S is turned through an angle approximately 270° from that shown in Figure 1 and lies across the bottom of the base B with the holder 11 turned to occupy the least space in a package. I found this feature very advantageous in packing a quantity of the devices for shipping purposes.

In Figures 3 and 4 the base B is made from a punching or stamping and the support S is made very similar to that shown in Figure 1 except in this form the extremity of the base 1 has a rolled over portion 17 to receive a pin 18 that passes through the turned over portion 19 of the short arm 6. In this form the upper end of the long arm 5 is straight and provided with a holder to receive a pivot pin 20 which carries a holder 11 which may be exactly like that shown in Figure 1 but as indicated is somewhat smaller and its outer curved ends provided with a ball link member 21 to provide the proper gripping effect on the flash light after it has been inserted into the holder 1. In this form the base B is provided with an orifice 22 so the base may be attached

to a hook or equivalent if the occasion warrants. Also the arm 6 is provided with an orifice 23 for a similar purpose with a cooperative hole in the base B, if found necessary for certain work. These holes permit the hanging up of the device in most any position. The same hole 23 is in the arm 6 in the structure shown in Figures 1 and 2. The structure shown and described can be made at a very low cost and yet perform services for which it is intended in a highly efficient manner. Having thus described my invention, what I claim is:

1. A flash-light holder including a single piece base adapted for insertion back of a user's belt, the base having an extension on one side thereof, 15 a single piece L-shaped support member having long and short arms with the short arm pivotally mounted on the base extension, the short arm in one position of the support member resting on the base at the extremity thereof, while in this position the long arm of the L extends upwardly from the base and a member of resilient material, for gripping a flash-light, rotatably mounted at the free end of said support member.

2. A flash-light holder as set forth in claim 1 further defined in that the free end of the long arm is bent over and has the material of the bent-over portion and a part opposite it formed into a ball seat and means for adjusting the position of the bent-over portion.

3. A flash-light holder including a base formed of a single piece of wire with a projection at one edge, an L-shaped support member having a short arm pivoted to the outer part of said projection and in one position of operation the short arm rests on the projection, while in this position the long arm extends upwardly away from the base and a member of resilient material for gripping

4 a flash-light, rotatably mounted on the free end of the long arm of the support member.

5 5. A flash-light holder having a base that can be readily slipped back of a user's belt or hung on a support, said base having an extension on one side, a support member pivoted to the base extension and having a part resting flatwise on the base when said member is one position of operation, a gripping member rotatably attached to the support member for holding the flash-light, the support member being foldable over the opposite side of base from the first-mentioned position as and for the purpose described.

10 6. A flash-light holder including a single piece base having substantially a flat engagement area so it may be slipped back of a user's belt, a single piece flat stock L-shaped support member pivotally mounted at the horizontal arm of the L on the base at the extremity of one end so it will turn thereon through an angle of approximately 270° and a single member of resilient material for gripping a flash-light rotatably mounted at the free end of the support member so as to be rotated through 360° at any arcuate position of its mounting which of itself may be turned through an angle of approximately 180°.
